Filed June 30, 1965, Ser. No. 468,287
8 Claims. (Cl. 280—218)

ABSTRACT OF THE DISCLOSURE

A riding toy for children propelled by an occupant shifting his weight forwardly and rearwardly for fulcruming the toy about a pair of centrally disposed ground engaging wheels. The rear end of the toy includes a ground engaging member which converts downward movement of the rear end of the toy into a forward propelling force. An elastic member returns the ground engaging member to its initial position during forward fulcruming of the toy and a wheel on the front of the toy will rollingly support the front of the toy when it has been fulcrumed forwardly.

The present invention generally relates to a riding toy in the form of a wheeled vehicle which is occupant propelled.

An object of the present invention is to provide a riding toy which is propelled by the occupant thereof with the propulsion of the riding toy being intermittent and responsive to somewhat of a rocking movement of the occupant or shifting of the weight of the occupant in a forward and rearward direction for causing intermittent forward motion of the toy vehicle.

A further object of the present invention is to provide a riding toy or vehicle of the present invention which employs a ground engaging element including a cam structure associated therewith and associated with the toy vehicle so that when the occupant of the toy vehicle leans rearwardly or shifts his weight rearwardly, the cam structure will cause forward movement of the vehicle and subsequently when the occupant leans forward or shifts his weight forward, the cam structure will recondition itself to an original position so that the next increment of forward motion may be imparted by the occupant once again leaning rearwardly or shifting his weight rearwardly thereby producing an intermittent forward motion caused by the occupant shifting his weight to render a cam structure operative for propelling the vehicle and then permitting the cam structure to recondition itself to an initial condition.

Yet another object of the present invention is to provide an occupant propelled toy vehicle in accordance with the preceding object in which the cam structure includes an inclined trackway carried by a ground engaging element and a roller or wheel carried by the toy vehicle at the rear thereof for selectively rolling forwardly and rearwardly in the track so that as the wheel rolls forwardly and downwardly, the vehicle will be propelled and when the rear of the vehicle is lifted upwardly, a resilient element will return the track to its original position by pulling the ground engaging element forwardly.

Still another feature of the present invention is to provide a toy vehicle in accordance with the preceding objects in which the cam structure is in the form of an eccentric element swingably connected to the rear end of the vehicle in an eccentric manner so that the ground engaging surface thereof will cause propulsion of the vehicle as the point of pivotal connection moves forwardly since it will move in a circular path about the center of the ground engaging element.

Still another feature of the present invention is to provide an occupant propelled toy vehicle which is simple

2

in construction, easy to use, highly novel in operation and relatively inexpensive to manufacture and maintain.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of the occupant propelled riding toy of the present invention;

FIGURE 2 is a side elevational view of the construction of FIGURE 1 illustrating one increment of forward movement being just completed;

FIGURE 3 is a front view of the toy;

FIGURE 4 is a rear view of the toy;

FIGURE 5 is a bottom view of the toy;

FIGURE 6 is a longitudinal, sectional view of the toy illustrating the structural features thereof;

FIGURE 7 is a detailed sectional view taken substantially upon a plane passing along section line 7—7 of FIGURE 6 illustrating the structure of the wheel rollingly supported in the inclined tracks;

FIGURE 8 is a detailed sectional view taken substantially upon a plane passing along section line 8—8 of FIGURE 6 illustrating the actual construction for supporting the large support wheels;

FIGURE 9 is a partial side elevational view with portions thereof in section and illustrating another embodiment of the invention;

FIGURE 10 is a view similar to FIGURE 9 but with the modified form of the invention at the end of a forward increment of movement; and

FIGURE 11 is a detailed view illustrating the manner in which the resilient return band is attached to the cam structure in FIGURES 9 and 10.

Referring now specifically to the drawings, the numeral 10 generally designates the occupant propelled riding toy or vehicle of the present invention which includes an elongated relatively narrow body 12 which is constructed of plastic, wood, metal or the like and may be hollow, partially hollow, or solid in construction. Mounted at the front lower end of the body 12 is a caster wheel 14 rotatably supported at one end of a curved yoke 16 that is swivelly supported by a supporting structure 18 received in a cavity in the body 12 so that the caster wheel 14 may rotate about an axle 20 and also swivel about a generally vertical axis perpendicular to the axle 20 and offset in relation thereto.

Adjacent the upper surface of the body 12, there is provided a substantially flat seat 22 for an occupant 24 and the seat 22 is supported by a supporting base or pedestal 26. Disposed forwardly of the seat 22 is a pair of inclined handles 28 which has the forward end thereof extending downwardly as at 30 with both its forward and rear ends thereof being secured to the body 12 in any suitable manner such as being secured thereto or embedded therein. Thus, the handles 28 which are in the form of a pair of generally parallel and laterally spaced rods or tubes may be easily grasped by the hands 32 of the occupant 24.

The feet of the occupant are supported on lateral supports 34 which may be integral with or glued to the body 12 such as at 36 and at the outer end of each support 34, there is provided an upstanding guard 38 to retain the feet 65 of the occupant 24 in position on the foot support 34.

Extending laterally of the body 12 is an axle housing 40 which extends under the foot support 34 and is tubular in nature for receiving the axle 42 having main supporting wheels 44 journaled on reduced ends thereof with the wheels 44 being secured in place by a retaining cap 46 which may be conveniently of the drive-on type.

As illustrated in FIGURE 6, the foot support 34 is provided with depending flanges 48 which serve to anchor and support the axle housing 40 in place with the axle housing being secured to the support 34 and flanges 48 in any suitable manner such as by fasteners, clamps, suitable adhesives or the like.

The forward end of the body 12 is provided with an enlarged portion 50 forming a simulated head having simulated eyes 52, mouth 54, nose 56 and the like to increase the desirability of the toy vehicle by simulating an insect, animal or the like. Extending longitudinally of the body 12 is a plurality of reinforcing ribs 58 which rigidifies the body and retains the same in substantially rigid condition. The material from which all of the components is constructed may vary depending upon the cost, durability and appearance characteristics desired in the item.

At the rear of the body 12, there is provided an elongated groove 60 communicating with the bottom edge and rear edge of the body 12 with the bottom of the groove 60 being inclined as at 62 from the bottom edge of the body 12 just rearwardly of the axle housing to the rear edge of the housing 12 adjacent the top edge thereof. Extending transversely of the groove 60 adjacent the rear end thereof is an axle 64 having end caps 66 thereon. Rotatably journaled on the axle 64 is a rotatable wheel 68. The axle 64 has spacing elements 70 thereon which engage the inner surface of the groove 60 for reinforcing the same and retaining the side walls of the grooves 60 in parallel relation and also serving to position the wheel 68 in a manner described hereinafter.

Disposed in the groove 60 is a ground engaging element 72 which includes an elongated hollow body 74 having a ground engaging foot 76 at the forward end thereof and a depending rear end portion 78 terminating in a pair of outwardly extending ground engaging feet 80 which define a generally shallow V-shaped notch 82 therebetween. The depending portion 78 supports the rear end of the elongated housing 74 at a higher elevation than the front end thereof which has the foot 76 depending therefrom and the foot 76 combined with the two feet 80 form generally a three-point engagement of the ground engaging element 72 with the ground surface.

The interior of the elongated body 74 is hollow and provided with a longitudinal track 84 which receives the roller 68. The side walls of the track are designated by numeral 86 and the side walls 86 each have a longitudinal slot 88 formed therein for receiving the axle 64 and enabling the wheel or roller 68 to roll along the inclined trackway 84 in a manner described hereinafter.

An elastic or resilient cord or spring device 90 is attached to a loop or eye 92 on the front edge of the traction member 72 and the other end of the resilient member 90 is attached to a depending hook or eye 94 carried by the bottom of the body 12 adjacent the forward end thereof so that when the body 12 moves forwardly in relation to the ground engaging traction member 72, the resilient member 90 will be elongated so that when the occupant 24 of the toy vehicle leans forwardly and shifts his weight forwardly and the traction member 72 is disengaged from the ground surface, the biased or stretched resilient member 90 will pull the traction member 72 forwardly from the position illustrated in FIGURE 2 to the position illustrated in FIGURE 6.

In operation of this form of the invention, the occupant 24 will normally board the vehicle when it is in the condition illustrated in FIGURE 6. He will be seated on the seat 22 and his feet will be placed on the supporting elements 34 and he will grasp the handles 28 and lean rearwardly. This will tend to pivot the body 12 about an axis generally defined by the wheel axle 42 or about an axis defined at the bottom edges of the wheels. This will exert a downward force on the axle 64 and the wheel 68. Since the wheel 68 rollingly engages the surface of the track 84 which is inclined, the body 12 will be propelled forwardly inasmuch as the ground engaging ends

80 and 76 will prevent rearward movement of the ground engaging member 72. Thus, the vehicle body 12 will be propelled forwardly the horizontal length of the slots 88 and at the same time the rear end portion of the body 12 will lower itself as the roller 68 proceeds down the track 84 so that the vehicle body 12 and the traction member 72 will be in the position illustrated in FIGURE 2 which represents the completion of an increment of forward movement and it is pointed out that the forward end of the body 12 has been slightly elevated above the ground surface. Then the occupant 24 will or shift his weight forwardly by leaning forwardly during which time he may grasp the forward or downwardly inclined portions of the handle 30 and rock his body forwardly while remaining on the seat thus causing the body 12 to pivot forwardly thus elevating the rear end of the body 12 and lowering the front end thereof which will release the ground engaging member 72 so that it can move forwardly in relation to the body 12 inasmuch as there will be substantially no weight urging the ground engaging member against the ground. As the rear end of the body 12 is elevated, it will elevate the foot 76 from the ground and the feet 80 will be slid along the ground surface by the flexible resilient tension member 90 which has been elongated during the initial forward increment or movement of the body 12. Thus, as the resilient member 90 returns to its normal position, it will pull the traction member forward at a rapid rate somewhat in the nature of a quick jerk which will rapidly move the traction member 72 back to its original position illustrated in FIGURE 6 so that a subsequent increment of forward movement may be accomplished by repeating the above described operation.

FIGURES 9-11 disclose a modified form of the above invention which has a modified body 12' having a recess or slot 100 formed in the bottom rear surface thereof for pivotally receiving an arcuate member 102 on a transverse pivot pin or shaft 104. The arcuate member 102 may be semi-circular in configuration with one end thereof pivoted to the body 12' by the pivot pin or axle 104. The surface of the arcuate member 102 designated by numeral 106 engages the ground surface and may be provided with traction producing material such as coating of abrasive material, rubber or the like to prevent slippage. Thus, the surface 106 is eccentric in relation to the pivot axis 104 so that when the arcuate member 102 is oriented in the position illustrated in FIGURE 9 and a vertical force is applied to the body 12' adjacent the rear thereof, the arcuate member 102 will be caused to roll forwardly by virtue of the surface 106 rolling along the ground surface thus propelling the body 12' forwardly an increment of movement as the lower end of each body 12' lowers to the position illustrated in FIGURE 10. Then, by the occupant of the vehicle shifting his weight forwardly in the same manner as in connection with the device disclosed in FIGURES 1-8, the arcuate member 102 is returned to its normal position by a resilient flexible elastic element 108 similar to the elastic element 90 which is attached at one end to the body 12' by a hook 110 and which is attached at its other end to the arcuate member 102 by a fastener bolt or other means 112 receiving in a recess 114 in the peripheral surface 106 of the arcuate member 102 so that the surface of the arcuate member will be substantially constant and the groove is provided in communication with the recess 114 as designated by numeral 116 to receive the resilient cord 108 when the arcuate member 102 is in the position illustrated in FIGURE 10. A stop lock 118 is provided in the recess 100 to limit the forward swinging movement of the arcuate member 102 about the transverse pin or axle 104 so that the arcuate member 102 will always return to its normal position illustrated in FIGURE 9 when the body 12' is pivoted forwardly about the lower edge of the wheels or the axis of the wheels 14'. The arcuate member 102 serves as a traction member in the same manner as the member

72 and serves to propel the body 12' forwardly in generally the same manner for moving the body in a linear forward direction as the lower end of the body is forced downwardly with the traction element converting a portion of the downward vertical movement of the rear end of the body into forward movement thereof.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An occupant propelled riding toy vehicle comprising a body including means for supporting an occupant thereon, wheel means carried by said body intermediate the forward and rear ends thereof to enable movement of the body and also forming means by which the body may be tilted forwardly and rearwardly, ground engaging means connected with a portion of said body in spaced relation to the wheel means for exerting longitudinal force on said body when the portion of the body with which the ground engaging means is associated is moved in a vertical plane by the occupant exerting a fulcruming force thereon in one direction thus moving the body longitudinally, and means interconnecting the body and the ground engaging means for returning the ground engaging means to an initial position without exerting longitudinal force on the body when the portion of the body with which the ground engaging means is associated is moved in a vertical plane by the occupant shifting his weight longitudinally of the body to cause the body to fulcrum about the wheel means in the opposite direction, said ground engaging means including a ground engaging member having an inclined trackway therein with the upper end of the trackway being remote from said wheel means, said body including a roller journaled thereon in rolling engagement with the trackway so that when the roller is in the upper end of the trackway and a downward force is exerted on the portion of the body having the roller thereon, the roller will roll down the trackway and the body will move longitudinally.

2. The structure as defined in claim 1 wherein said body includes spaced mounting members on the lower surface thereof, said roller having at least a portion thereof received between the mounting members, an axle extending through the roller and supporting the roller from said mounting members, said ground engaging member having slot means disposed above the trackway receiving said axle thereby enabling longitudinal movement of the roller along the trackway and guiding the roller in relation to the trackway during movement therewith.

3. The structure as defined in claim 2 wherein the portion of said body remote from said ground engaging member is provided with supporting means to engage a supporting surface when the body is fulcrumed about the wheel means to permit return of the ground engaging member to an initial position.

4. The structure as defined in claim 3 wherein said body includes an occupant's seat disposed in longitudinally spaced relation to the wheel means, and handle means mounted on said body on the opposite side of said wheel means from the occupant's seat, and foot supporting members carried by said body for receiving the feet of an occupant of the seat to enable shifting of the occupant's weight forwardly and rearwardly in relation to said body.

5. An occupant propelled riding toy vehicle comprising a body including means for supporting an occupant thereon, wheel means carried by said body intermediate the forward and rear ends thereof to enable propulsion of the body and also forming means by which the body may be tilted forwardly and rearwardly, ground engaging means

at one end of said body in spaced relation to the wheel means for exerting longitudinal force on said body when the end of the body with which the ground engaging means is associated is moved downwardly by the occupant exerting a downward force thereon thus moving the body longitudinally, and means interconnecting the body and the ground engaging means for returning the ground engaging means to an initial position without exerting longitudinal force on the body when the end of the body with which the ground engaging means is associated is moved upwardly by the occupant shifting his weight longitudinally of the body to cause the body to fulcrum about the wheel means, the end of said body remote from said ground engaging means being provided with a supporting wheel, said ground engaging means including a ground engaging member having an inclined trackway therein with the upper end of the trackway being remote from said body, said body including a roller journaled thereon in rolling engagement with the trackway so that when the roller is in the upper end of the trackway and the downward forces exerted on the end of the body having the roller thereon, the roller will roll down the trackway as the body moves longitudinally, said body including an inclined slot communicating with the lower surface thereof with the walls of the slot journaling said roller, said ground engaging member having said trackway formed in a hollow projection received in said slot with the trackway being defined by a bottom and parallel side walls, said side walls defining the trackway including slots therein, said roller being disposed between the slotted side walls and being supported by a transverse axle extending through the slots and supported in said body.

6. The structure as defined in claim 5 wherein said means for returning the ground engaging member to a normal position includes a flexible elastic member interconnecting said body and adjacent end of said ground engaging member.

7. The structure as defined in claim 5 wherein said body includes an occupant's seat disposed longitudinally in spaced relation to the wheel means, and handle elements mounted on said body on the opposite side of said wheel means, said body including foot supporting members for receiving the feet of the occupant whereby an occupant on the seat may shift his weight forwardly and rearwardly in relation to said body.

8. An occupant propelled riding toy vehicle comprising a body including means for supporting an occupant thereon, wheel means carried by said body intermediate the forward and rear ends thereof to enable propulsion of the body and also forming means by which the body may be tilted forwardly and rearwardly, ground engaging means at one end of said body in spaced relation to the wheel means for exerting longitudinal force on said body when the end of the body with which the ground engaging means is associated is moved downwardly by the occupant exerting a downward force thereon thus moving the body longitudinally, and means interconnecting the body and the ground engaging means for returning the ground engaging means to an initial position without exerting longitudinal force on the body when the end of the body with which the ground engaging means is associated is moved upwardly by the occupant shifting his weight longitudinally of the body to cause the body to fulcrum about the wheel means, the end of said body remote from said ground engaging means being provided with a supporting wheel, said ground engaging means including a ground engaging element including a partially circular peripheral ground engaging surface, means journaling said ground engaging member for pivotal movement on said body whereby the axis of pivotal movement of the ground engaging member is eccentric in relation to the ground engaging surface, means limiting the pivotal movement of the ground engaging member towards the body so that the peripheral surface thereof will be orientated so that upon downward force being exerted

on the end of the body to which the ground engaging member is attached, the ground engaging member will roll on its peripheral surface thus propelling the body forwardly, said means returning the ground engaging means to a normal position including a flexible elastic member interconnecting the ground engaging element and said body, said peripheral surface of the ground engaging element including a groove receiving the elastic cord when the ground engaging element is operative to propel the body.
